ROBERT H. COBB, OF RAT PORTAGE, CANADA.

TELLTALE.

No. 805,713.

Specification of Letters Patent.

Patented Nov. 28, 1905.

Application filed April 12, 1905. Serial No. 255,140.

To all whom it may concern:

Be it known that I, ROBERT H. COBB, a subject of the King of Great Britain, residing at Rat Portage, county of Rainy River, in the 5 Province of Ontario, Canada, have invented certain new and useful Improvements in Telltales; and I do hereby declare that the following is a full, clear, and exact description of the invention, such as will enable others skilled in 10 the art to which it appertains to make and use the same.

This invention relates to new and useful improvements in semaphores; and it consists in the addition of a synchronally-operating telltale acting in the same manner and direction 15 as the semaphore.

The object of the invention is to enable an operator to determine whether or not a semaphore is operated when located at a distance 20 from a signal-tower or from the station of the operator; and it consists in certain features of novelty in the detail construction and arrangement of the mechanism hereinafter more specifically referred to.

25 In the annexed drawings similar numerals of reference indicate corresponding parts in both figures, wherein—

Figure 1 is an elevational view showing my improved semaphore and telltale connected, 30 and Fig. 2 is an elevational view of the semaphore standing alone.

Referring to the parts, 1 is a semaphore-post upon which is pivotally supported the semaphore-arm 2, carried upon the pivot 3, 35 projecting from said post 1, as shown in Fig. 2. Extending from the rearward extension 4 of the semaphore 2 is a cable 5, which extends downwardly to the arm 6 of the bell-crank lever, which is pivoted at 7 on the 40 bracket 8, projecting laterally from said post 1. Extending thence rearwardly from the vertical leg of said bell-crank lever is a cable 9, which extends to and is connected with the wheel or drum 10, supported on the bracket 45

11 at a distance from said semaphore-post 1. In convenient proximity to the said wheel 10 is a smaller post 12, upon which is carried the telltale feature of the device. This telltale comprises the pivoted arm 13, having the rearward-extending portion 14, which is connected by the cord or cable 15 with a bell-crank lever 16, which is pivotally supported on said post 12, while a cable 17 extends from said bell-crank lever 16 to a corresponding bell-crank lever 18, which is carried by the bracket 19, 50 projecting from said post 1. Extending

upwardly from the bell-crank lever 18 is a cable 19, which is connected with the semaphore-arm 2 on the opposite side of the pivot 3 from the point of connection of the cable 5. 60 In convenient proximity to the post 12 is a locking-post 20, provided with any convenient locking means, as pins 21, adapted to serve to prevent movement of the arm 13 upon its pivot. 65

It will be evident from the connection of the parts that when the semaphore-arm 2 is manipulated by means of the operating-lever 22 and cable 9, a corresponding movement of the telltale-arm 13 will result from the 70 connection described. The post 12 should be low and convenient to the wheel 10 to enable the operator of the semaphore when wishing to put the semaphore into position to loosen said wheel 10 and pull the telltale 13 75 down, where it may be fastened in any convenient position with relation to the post 20 by means of the pins 21 or other equivalent locking device. This movement will result in a corresponding movement of the semaphore-arm 2, and owing to the means for locking the telltale-arm 13 no weights will be required to balance the semaphore-arm 2, and consequently there will be no danger of the device getting out of order. 80

It will be evident that when the arm 13 of the telltale is lowered with relation to the post 20 there will result a draft on the cable 15, which will rock the bell-crank levers 16 and 18, thereby causing draft upon the cable 19, 90 extending from the bell-crank lever 18, and a corresponding downward movement of the arm 2 will result, and when the lever 22 is manipulated to cause draft upon the cable 9 in the direction indicated by the arrow in Fig. 95 1 there will result a rocking of the bell-crank lever 6, which will cause a downdraft upon the cable 5, thereby raising the arm 2 to the position shown in Fig. 2. This is a great advantage in the operation of the device, as it will 100 be possible to arrange the telltale and operating-lever at a considerable distance from the semaphore-post 1. Without the connection herein shown there is no means for determining whether the semaphore is actually operated or not if the semaphore-post 1 and its connected posts should happen to be located behind an obstruction or during snow-storms, &c., which render the semaphore 2 invisible. 105

On the post 1 is located a bracket 23, which 110 serves as a stop to prevent excessive movement upwardly of the semaphore-arm 2, and

it will be evident that when the arm 2 has reached the position shown in Fig. 2 the rear end portion 4 of said semaphore-arm will strike said stop-bracket 23.

5. The semaphore-arm 2 is provided with different-colored plates 24 and 25, and it will be evident from the location of the lamp 26 that the plate 24 is in coincidence with said lamp when the arm 2 is in the position shown in Fig. 10. 2 and the plate 25 is in coincidence with said lamp when the semaphore-arm occupies a lowered position. Thus different light-signals may be given.

15. While I have shown in the accompanying drawings the preferred form of my invention, it will be understood that I do not limit myself to the precise form shown, for many of the details may be changed in form or position without affecting the operativeness or utility 20. of my invention, and I therefore reserve the right to make all such modifications as are included within the scope of the following claims or of mechanical equivalents to the structures set forth.

25. Having described my invention, what I claim, and desire to secure by Letters Patent, is—

1. In a telltale for semaphores, a plurality

of semaphore-posts, a bell-crank lever on one post, a bell-crank lever on the other post, a plurality of pivotally-supported semaphore-arms, cables connecting said bell-crank levers and one of said semaphore-arms, a cable connecting two of said bell-crank levers, and a cable extending from the third bell-crank lever to manipulating means.

2. In a telltale for semaphores, a plurality of semaphore-posts, a pivoted arm on each of said posts, a pair of bell-crank levers pivotally supported on one post, cables connecting the horizontal arms of said bell-crank levers with the semaphore-arm on said post, a bell-crank lever on the other post, a cable connecting the horizontal arm of said bell-crank lever with the telltale-arm on said post, a cable connecting the vertical legs of two of said bell-crank levers, and a cable running from the other bell-crank lever to manipulating means.

In witness whereof I have hereunto set my hand in the presence of two witnesses.

ROBERT H. COBB.
